Julian Pollock
ATTORNEY

UNITED STATES PATENT OFFICE

HARRY KASS, OF BROOKLYN, NEW YORK

SELF-FITTING APRON

Application filed April 15, 1931. Serial No. 530,232.

This invention relates to new and useful improvements in a self-fitting apron.

The invention has for an object the construction of a self-fitting apron which is characterized by an upper body having front and back portions, a skirt portion attached upon the front portion and having sides extending part way across the back and resilient means upon the lower edge of the back portion between the sides for holding the apron upon the wearer.

The advantage of an apron constructed according to this invention is that it may be engaged in place on a wearer and taken off whenever desired without the inconvenience of tying and untying apron strings.

It is a still further object of this invention to arrange the back of the body pleated so as to be capable of stretching as allowed under resilient means.

A still further object of this invention is the construction of large arm holes in the body portion and the provision of a small width of cloth between the armholes and the back sides of the skirt portion.

As another object of this invention, it is proposed to terminate the body portion so that substantially no material exists between the armholes and the sides of the skirt portions.

Another object of this invention is the construction of inclined seams between the armholes and the sides of the skirt portion for the proper connection of the parts.

A still further object of this invention is the provision of means for changing the distance between the ends of the resilient means for controlling the resiliency.

A still further object of this invention is the provision of a self-fitting apron which is of simple, durable construction, desirable in use and efficient in action and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing, forming a material part of this disclosure:

Fig. 1 is a pictorial view of a lady wearing an apron constructed according to this invention and viewed from the back.

Fig. 2 is a fragmentary enlarged sectional view taken on the line 2-2 of Fig. 1.

Fig. 3 is a fragmentary enlarged elevational view of a portion of Fig. 1 showing in particular the corner between lower edge of the upper body portion and the vertical side of the skirt portion.

Fig. 4 is a view similar to Fig. 3 but illustrating a modified construction.

Fig. 5 is a view similar to Fig. 3 but illustrating a still further modified construction.

Fig. 6 is a fragmentary enlarged detailed view taken on the line 6-6 of Fig. 5.

Fig. 7 is a fragmentary view similar to Fig. 1 showing another modified construction.

The self-fitting apron, according to this invention, comprises an upper body 10 having a front portion to the front of the person illustrated in Fig. 1 and the back portion extending from the shoulder down to the waistline. A skirt portion 11 connects with the front portion and has sides 12 extending part way across the back. Resilient means 13 is located upon the lower edge of the back portion between the sides 12 and serves to hold the apron upon a wearer.

The body portion 10 has a neck opening 14 and arm openings 15. The back portion 10 is formed with a plurality of pleats 16 so as to allow for expansion. The resilient means 13 is in the form of ruffled binding strips 17 engaged on opposite sides of the edge of the back portion and covering an elastic member 18.

The material on the back portion of the upper body and the sides 12 is so constructed that inclined seams 19 are produced which extend from the armholes to the corner between the bottom edge of the back portion of the sides 12. Stitches 20 serve to hold this seam closed.

In the modified construction illustrated in Fig. 4 the material of the back portion of the upper body and the vertical sides 12 are so constructed that practically no goods is dis-

posed between the armholes of the corner where the bottom edge of the back portion meets the vertical sides 12. This point is indicated on the drawing by reference numeral 21.

In Figs. 5 and 6 a modified construction of the invention has been disclosed in which a means is provided for changing the distance between the ends of the resilient means 13 to change the resiliency thereof. This means is in the form of an inclined casing 22 at each of the sides of the garment. Each casing lies along the same path as does seam 19. Each casing 22 is of hollow construction and has an opened side 23 into which the ends of the elastic 18 may engage. A transverse rivet 24 engages through the end of the elastic 18 and thru the side slots 25 formed in the sides of the casing. The near sides of the slots 25 are formed with a plurality of teeth 26. The skirt portion 11 is connected with the casing 22 by reason of engaging within a groove 27 in the casing. Stitches 28 engage through the casing and the skirt portion 11 for connecting these parts together. The lower edge of the back portion of the upper body is connected with the casing 22 from the edge of the armhole 15 to a point indicated on the drawing by reference numeral 28. This point is located but a short distance from the armhole so that the remaining portion 29 of material along the casing is free.

To change the tension of the elastic 18 it is necessary to move the rivet 24 along the slots 25 so that different points upon the teeth 26 are engaged. This will cause a change in the location of the elastic 18 to a position, for example, as indicated by the dot and dash lines 30. When the position of the elastic 18 is changed to the dot and dash lines position, a loop will occur at the point 28 but it does not interfere with the operation of the apron.

The operation of the self-fitting apron can be understood by assuming it on a person as illustrated on Fig. 1. To remove it, it should be slipped upwards so that the neck 14 passes over the wearer's head and the arms. The apron can be re-engaged in place by slipping it down upon the person.

In Fig. 7 a pair of elastics 18' have been shown joined by the apron portion 18^a.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In a self-fitting apron, having an upper body having a front and back portion, and a skirt portion attached upon said front portion and having sides extending part ways across the back, means for holding the apron

on a wearer comprising resilient means upon the lower edge of the back portion between the sides, and means for changing the resiliency of the resilient means.

2. In a self-fitting apron, having an upper body having a front and back portion, and a skirt portion attached upon said front portion and having sides extending part ways across the back, means for holding the apron on a wearer comprising an elastic strip upon the lower edge of the back portion between the sides, and means for changing the neutral distance between the ends of the elastic strip for changing its resiliency, comprising casings attached upon the apron on lines between the armholes and the points formed by the bottom edge of the back portion and the vertical sides, rivets engaged upon the elastic strip ends and passing through slots in said casing, and teeth formed in said slots for holding said rivets in various adjusted positions.

3. In a self-fitting apron, an elastic strip for holding the apron on a wearer, and means for changing the resiliency of the elastic strip, comprising casings attached upon the apron at each of the ends of the elastic strip, and means for holding the elastic strip ends in various positions along the casings.

4. In a self-fitting apron, an elastic strip for holding the apron on a wearer, and means for changing the resiliency of the elastic strip, comprising casings attached upon the apron at each of the ends of the elastic strip, and means for holding the elastic strip ends in various positions along the casings, comprising rivets engaged upon the elastic ends and passing through slots in the casings, and means for holding the rivets in fixed adjusted positions along the length of the slots.

In testimony whereof I have affixed my signature.

HARRY KASS.
